UNITED STATES PATENT OFFICE.

CHARLES F. RITCHIE, OF BRIDGEPORT, CONNECTICUT, ASSIGNOR TO EDWARD R. IVES, OF SAME PLACE, AND CORNELIUS BLAKESLEE AND EDWARD G. WILLIAMS, OF BROOKLYN, NEW YORK.

DESIGN FOR A TOY FOR EXPLODING CAPS AND FULMINATES.

SPECIFICATION forming part of Design No. 12,749, dated February 7, 1882.

Application filed November 29, 1881. Term of patent 7 years.

To all whom it may concern:

Be it known that I, CHARLES F. RITCHIE, of Bridgeport, in the county of Fairfield and State of Connecticut, have invented a new Design for a Toy for Exploding Caps and Fulminates, of which the following is a specification.

My design consists in a toy consisting of a handle, diverging portions beyond the handle, and heads at the ends of the diverging portions, one serving as a cap or fulminate receptacle and another as a hammer.

The accompanying drawing illustrates a toy embodying my design.

A designates the handle, which as here shown has a curved outline and an ornamental surface.

B B' designate two diverging portions extending from the handle A. At the outer ends of these diverging portions are two heads, C C'. The heads shown are of grotesque appearance. The mouth of the head C forms a cap or fulminate receptacle, and the nose of the head C' forms a hammer for exploding caps

or fulminates in the said receptacle. The diverging portions B B' have the appearance of long necks belonging to the heads C C'.

This toy is of unique design, and hence will afford much amusement.

What I claim as my invention, and desire to secure by Letters Patent, is—

1. The design for a toy for exploding caps and fulminates, consisting of a handle, diverging portions extending therefrom, and heads at the outer ends of the diverging portions, one forming a cap or fulminate receptacle and another a hammer, substantially as specified.

2. The design for a toy for exploding caps and fulminates, consisting of the handle A, the diverging portions B B', and the heads C C', one forming a cap or fulminate receptacle and the other a hammer, substantially as specified.

CHAS. F. RITCHIE.
